UNITED STATES PATENT OFFICE.

ALEXANDRE HURTUBISE, OF SAGINAW, MICHIGAN.

SLEIGH-NOSE.

SPECIFICATION forming part of Letters Patent No. 514,469, dated February 13, 1894.

Application filed August 26, 1893. Serial No. 484,076. (No model.)

To all whom it may concern:

Be it known that I, ALEXANDRE HURTUBISE, a citizen of the United States, residing at Saginaw, in the county of Saginaw and State of Michigan, have invented a certain new and useful Sleigh-Nose; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention is a nose for sleighs, especially logging sleighs.

It has been common to form the sleigh runner with a crook in front, either by using timber that grew in that shape, or by bending it, or by cutting the timber in said shape, and then to prevent splitting and breaking when under strain, ironing the runner over the nose or crook either by a continuation of the shoe, or by another band riveted thereto, requiring a great deal of careful work in the forming of the runner and in ironing it so as to withstand the strain. I overcome this by using a nose hereinafter described, which I am able to fit onto a runner sawed straight on its top surface throughout its entire length.

In the drawings, Figure 1 is a side elevation of the runner provided with my invention. Fig. 2 is a top view of the same. Fig. 3 is a side elevation of the sleigh nose. Fig. 4 is a view of the same in part sectional on lines X—X, Fig. 3. Figs. 5 and 6 are side elevations of the invention showing different constructions, and Fig. 7 is a view of Fig. 6, in part sectional on lines X—X, Fig. 6.

A is the runner, B the shoe. The runner A, as previously stated, has a flat top surface, the lower surface bowing up, as is common, to the line of the top surface.

C is the sleigh nose and is preferably of metal. It may be of wood properly ironed.

1 is the body of the nose, 2 an opening to receive the shaft connecting it to the other runner, and 3 a lug for securing the draft. The latter may be omitted and the draft applied through the opening 2. The upper surface and end 4 of this nose is curved in form

of the ordinary sleigh nose. The bottom 5 is flat and fits upon the top of the runner A, as shown.

In Figs. 1, 2, 3, and 4 I have illustrated a nose formed with a central rib or body 1, having projecting flanges above and below as 4, and 5, with the hole 2 formed in this central rib 1. In Figs. 5, 6, and 7, I have shown a nose made with sides 6, 6, and a central rib 1, with hollows between the rib and sides, the sides being on line with the sides of the runner.

In Fig. 1 I have shown the shoe B extending upward beyond the top line of the runner and in front of the nose, thus serving to strengthen the means of securing the nose to the runner, which as here shown, is by the bolts D, passing through the body or rib 1, through the runner and shoe.

A special feature of my invention is that it can be applied to any runner by cutting off the front of the runner, forming a straight top surface, and bolting the nose to it. It can thus be applied to runners of the old construction that have been broken in front. Then, too, they can be replaced. Experience shows that the parts commonly broken in logging sleighs is the nose.

By using my invention the runner can be made to last a long time, thus causing a great saving to the user. Again, if the runner breaks, the nose, shoe, and shoe can be removed from the old runner, a new one sawed out at once, the parts bolted thereto, and the damage remedied in short order without resort to a blacksmith or mechanic. It will thus be seen that my invention is of special advantage to timber and logging operators.

Having thus described my invention, what I claim as new, and desire to secure by Letters Patent, is—

1. In a sleigh runner of the class described a removable metal nose for the same consisting of a piece of metal of the width of the runner edge having its under surface adapted to rest upon the said edge, holes through the body of the metal to receive bolts to secure the same to the sleigh runner, the front end of the said metal nose being rounded so as to form a continuation of the beveled end of

the runner, and having an eye transversely through the rounded end to receive the cross bar connecting the two runners, substantially as specified.

5 2. A metal nose for sleigh runners of the class described, consisting of a piece of metal having its body formed like a T rail, the lower flange resting upon the upper edge of the runner, the upper flange forming a continuation of the upper edge of the runner when secured thereto and bowing over in the usual nose

shape on a line with the beveled edge of the runner, and provided with holes for bolts to secure it, to the runner, and eyes for receiving the cross piece, substantially as specified. 15

In testimony whereof I affix my signature in presence of two witnesses.

ALEXANDRE HURTUBISE.
